Fig. 12

*Fig. 13Fig. 14*FIG. 1 is a perspective view of a lavatory fitting showing my new design;

FIG. 2 is a top plan view of the same;

FIG. 3 is a front elevational view thereof;

FIG. 4 is a rear elevational view of the fitting;

FIG. 5 is a side elevational view of the lavatory fitting;

FIG. 6 is a perspective view of a modified form of the lavatory fitting shown in FIG. 1.

FIG. 7 is a top plan view of the modified form;

FIG. 8 is a front elevational view of said modified form;

FIG. 9 is a rear elevational view of FIG. 6;

FIG. 10 is a side elevational view of said modified form;

FIG. 11 is a perspective view of a further modified form of the lavatory fitting shown in FIG. 1;

FIG. 12 is a front elevational view of the FIG. 11 form;

FIG. 13 is a top plan view of the form shown in FIG. 11; and

FIG. 14 is a side elevational view of said further modified form.

The dominant features of the design reside in the portions shown in full lines.

The present application is a continuation of my prior co-pending design applications Serial Nos. D. 54,114, D. 54,106 and D. 54,111, all filed January 9, 1959.

I claim:

The ornamental design for a lavatory fitting or similar article, as shown and described.
